UNITED STATES PATENT OFFICE.

WILLIAM A. SCHLEICHER, OF CLEVELAND, OHIO.

DESIGN FOR A BUCKLE-FRAME.

SPECIFICATION forming part of Design No. 33,248, dated September 25, 1900.

Application filed April 19, 1900. Serial No. 13,544. Term of patent 14 years.

To all whom it may concern:

Be it known that I, WILLIAM A. SCHLEICHER, a citizen of the United States, residing at Cleveland, in the county of Cuyahoga and State of Ohio, have invented and produced a new and original Design for Buckle-Frames, of which the following is a full, clear, and exact specification, reference being had to the accompanying drawings, forming part of this specification.

In the drawings, Figure 1 is a perspective view of a harness-buckle frame embodying my design; Fig. 2, a plan view, and Fig. 3 a longitudinal central section thereof.

This invention relates to a design for a buckle-frame for use in connection with straps, such as harness-straps, particularly where it is desired to removably secure snap-hooks and other appliances to straps and for other uses of a similar character.

My new design consists in a buckle-frame having the shape and configuration substantially as shown in the drawings and as hereinafter described.

As shown in the drawings, a buckle-frame embodying my new design consists of a substantially-rectangular frame A, having longitudinal side bars a a, which side bars have substantially-flat outer and inner-surfaces a' a² and which are connected by the flat horizontal rear bar b, the forward bar c, and the lower intermediate cross-rod d. As shown, the rear bar d and the forward bar c extend across the upper portion of the buckle-frame, while the cross-rod d extends across the bottom of the same. At the forward end the side bars a a of the buckle-frame A extend forward some distance, as shown at a⁵, and are bridged by the base of the hook E, in which the buckle-frame terminates, said hook considerably reduced in width with reference to the buckle-frame.

The upper and lower edges a³ a⁴ of the side

bars a a each are continuously curved on parallel arcs, as shown, like the rockers of a rocking-chair. They meet and merge in the horizontal rear bar b, whose upper surface is slightly curved and whose forward edge is provided with a lip b', extending into the rectangular space between the bars b and c. 45

At the forward portions a⁶, where the forward bar c extends across, the side bars a a are also raised, forming arc-shaped projections, so as to meet and merge in the cross-bar c, as shown. The cross-bars b and c are 50 substantially in the same horizontal plane.

The intermediate lower connecting-rod d is arranged somewhat to the forward from the middle of the rectangular space between the front and rear bars a' a² and the side bars a a, and it affords a bearing for the pivoted strap-retaining tongue of the buckle, as indicated in dotted lines in Fig. 3 of the drawings. 55

The forward portions or arms a⁵ of the side bars a a, as shown, are bent downward 60 somewhat, thus forming an angle at e with respect to the side bars a a, which side bars, as seen in Fig. 3, are somewhat tapered forwardly and rounded at their ends a⁷, where they merge in and meet the base e' of the hook E. The said hook, as seen from Fig. 2, is considerably reduced in width with reference to the side bars a. 65

The inner edge e² of the base e' of the hook is somewhat curved, as shown, so that a D-shaped recess or opening is formed between it and the forward bar c and the arms a⁵. The hook E, as shown, is of well-known form. 70

The essential features of my design are the continuously-curved side bars in combination 80 with the upper cross-bars b c and intermediate lower rod d, arranged as shown, the cross-bar b being provided with an inwardly-extending lip b'.

The substantially-rectangular form of all 85 of the horizontal contours of the buckle, the

downwardly and forwardly extending arms α^5 , and the terminal hook, with its base bridging the said arms, so as to form a D-shaped opening, also enter into my design as important features.

A buckle so designed, particularly when applied to a strap, has a very pleasing and harmonious effect by reason of its simple and chaste contours.

10 It is manifest that this design is applicable to the buckle-frame irrespective of the strap-retaining device used in connection therewith,

whether the said retaining device be a pivoted tongue, fixed stud, or the like.

What I claim, and desire to secure by Letters Patent, is—

The design for a buckle-frame substantially as herein shown and described.

In testimony whereof I affix my signature in presence of two witnesses.

WILLIAM A. SCHLEICHER.
